UNITED STATES PATENT OFFICE.

CHARLES H. HOUSMAN, OF BOSTON, MASSACHUSETTS.

DESIGN FOR A CIGAR-CASE.

SPECIFICATION forming part of Design No. 22,418, dated May 9, 1893.

Application filed March 18, 1893. Serial No. 466,720. Term of patent 7 years.

To all whom it may concern:

Be it known that I, CHARLES H. HOUSMAN, a citizen of the United States, residing in Boston, in the county of Suffolk and State of Massachusetts, have invented and produced a new and original Design for a Cigar-Case, of which the following is a specification, reference being made to accompanying drawing, forming a part thereof.

10 The drawing shows in perspective my newly designed cigar case.

The cigar case consists of a hollow body rectangular in cross section, open at the upper end only, the back side of which extends 15 up above the opening a considerable distance and has a forwardly projecting flange upon

each side and at the top, thereby presenting to the eye a case which is rectangular in shape, and open at the front side from the top to a point about midway the height, the 20 flange giving to the upper part a finished appearance.

I claim—

The design for a cigar case, as herein shown and described.

In testimony whereof I have signed my name to this specification in the presence of two subscribing witnesses.

CHARLES H. HOUSMAN.

Witnesses:

BERNICE J. NOYES,

CHARLES B. CROCKER.
